UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed March 13, 1924. Serial No. 699,120.

This invention relates to drilling mechanism.

It has for its object to provide an improved drilling mechanism. Another object is to provide an improved drilling mechanism having an improved feeding means therefor. A further object is to provide an improved automatic feeding means. A still further object is to provide an improved feeding mechanism controlled by the operation of the drilling motor. A still further object is to provide an improved feed control mechanism which is responsive to vibrations set up in the drilling motor. Another object is to provide an improved feed control mechanism in combination with a pressure fluid actuated feed piston.

In the accompanying drawings I have shown for purposes of illustration two forms which my invention may assume in practice.

In these drawings,—

Fig. 1 is a side elevation partly broken away to show details of construction.

Fig. 2 is an enlarged fragmentary vertical longitudinal section through the feed piston.

Fig. 3 is a modified form of feed control means adapted to perform the same functions as the form shown in Fig. 2.

Fig. 4 is a transverse vertical sectional view taken substantially on line 4—4 of Fig. 1.

In the illustrative form of my invention I have shown the same embodied in a drifter type of drill comprising a combined supporting shell and feed cylinder 1 having a suitable clamping bracket 2 and longitudinally disposed guideways 3 within which the drilling mechanism 4 is slidably mounted as by gib 5. The drilling mechanism is shown as comprising a usual cylinder 6 having a hammer piston 7 reciprocably mounted therein and extending forwardly from which is a striking bar 8 having flutes on the periphery thereof adapted to cooperate with a chuck nut 9 fixed in the rear end of a chuck sleeve 10 rotatably mounted within a chuck housing 11 carried on the front end of the cylinder 6. It will be understood that usual pawl and ratchet mechanism (not shown) is used in combination with the piston 7 to impart rotation thereto and consequently to the chuck sleeve 10. Carried in the front end of the sleeve 10 is a usual chuck bushing 12 adapted to receive the shank of a steel 13

which receives impact blows from the piston 7.

Any suitable control valve mechanism generally designated 14 may be mounted within the rear head 15 of the cylinder 6 to control fluid flow to a fluid distributing valve mechanism generally designated 16 and to the feed cylinder 1, in a well known manner. The feeding mechanism comprises an arm 17 projecting rearwardly from the lower side of the head 15 and terminating in depending arms 18, 19 which carry at their lower end a boss 20 having a conical bore 21 within which is mounted a plug member 22 held therein as by a nut 23. Threadedly connected to a reduced extension 24 carried by the plug 22 is a hollow piston rod 25 projecting through a rear combined cylinder head and packing member 26. Mounted upon the front end of the piston rod 25 is a combined feed controlling valve and piston member 27 while the head 28 closes the front end of the cylinder 1.

More specifically, the combined piston and feed control valve comprises spaced piston ends 29 and 30 mounted upon a reduced portion 31 of the piston rod 25, while disposed upon the periphery of said reduced portion and between said end members is a valve supporting member comprising an annular portion 32 having a radial flange 33 at one end and a recess 34 at its other end to receive an annular ring 35 all of which are held in position as by a hollow flanged nut 36 screw threaded into the bore of the piston rod 25. The forward end of said nut rests against and holds a head 37 within said bore and which supports a fluid conducting tube 38 which projects forwardly from a chamber 39 formed in the plug member 22. Slidably mounted within the recess 40 formed by the annular portion 32, flange 33, and member 35 is a valve 41 having a radial expansible spring 42 disposed within an annular groove 43 formed in the periphery of said valve and adapted to frictionally engage the walls of the cylinder 1. Formed at the rear end of the valve 41 and on the inner surface thereof is an annular groove 43 adapted to allow communication when in the position shown in Fig. 2 between radial ports 44, formed in the rod 25 and annular portion 32, and the rear end of the piston 27 as by ports 45, passages 46 and 47 formed respectively in the annular portion 32 and end 110

member 29. It is to be noted that in the position shown in Fig. 2 the valve member 41 will just barely allow communication between said respective passages merely to hold the drill to the work and to compensate for leakage but that when the same is in the forward end of the recess 40, full communication will be permitted between the ports 44 and 45.

10 In order to allow flow of live pressure fluid to the rear side of the piston 27 to obtain a forward feed, I have provided a passage 48 in the arm 17, leading from the main control valve 14 through depending member 15 19, and which communicates with a passage 49 formed in the plug 22, the hollow portion of the piston rod, ports 44, annular groove 43, ports 45, passages 46 and 47 to the rear side of the piston. During this operation, 20 the front side of the piston 27 is vented to the atmosphere as through the hollow portion of the nut 36, passage 38, chamber 39, passage 50 formed in the arm 17 and depending member 18, and to the atmosphere as 25 through any suitable vent passage (not shown) in the valve 14. It is to be noted, however, that it is possible to vent the rear side of piston 27 and allow flow of live pressure fluid to the front side to impart reverse 30 feeding movement to the mechanism.

In the operation of my device the valve 14 will be turned to one position whereby pressure actuating fluid will flow through the distributing valve mechanism 16 to cause 35 reciprocation of the piston 7 and consequently rotation of the steel 13 in a usual manner. At the same time, fluid will flow (assuming forward feed) through the passages 48, 49, the hollow portion of the rod 25 and out through the ports 44 to the rear side of the piston 27 as before described. During this operation the piston 7 will set 40 up vibrations within the drilling mechanism due to the recoil of the piston 7 upon striking the steel 13. These vibrations will cause slight reciprocation of the piston rod 25, the result being a relative movement 45 between the frictionally held valve member 41 and the annular portion 32 such as to permit a greater opening between the ports 44 and 45 hence allowing a greater amount 50 of flow of live pressure fluid to the rear side of the piston 27 to feed the machine forwardly. It will thus be seen that the 55 greater number of recoil vibrations the piston 7 sets up, which is proportional to the speed of reciprocation of the piston 7, there will be a greater rate of feed due to the fact that the valve 41 will also move a 60 greater number of times and thereby allow a greater amount of fluid flow per unit of time than if a low vibration were set up due to a slow speed of the piston 7.

During the operation of the drilling 65 mechanism if the steel encounters soft mate-

rial the recoil of the piston 7 will not be as great as though the steel encountered hard rock. The result is the piston 7 is slowed down with a consequent reduction of vibration and also a reduction of fluid flow to the rear side of the piston 27 due to slower valve movement thereby reducing the amount of feed. It often occurs that the steel will encounter material which will offer varying degrees of resistance to the steel rotation, 75 which resistance also varies the speed of reciprocation of the piston 7 with a consequent reduction of vibration and flow of fluid for forward feeding. If it is now desired to reverse the feed valve 14 will 80 be thrown to reverse position whereby the bore of the rod 25 will be vented to atmosphere in a usual manner and fluid admitted to the front side of the piston as through the passage 50 and tube 38 to feed the mechanism in a reverse direction. During initial reverse movement of piston 27, valve 41 will be frictionally held until engaged by the ring 35 at which time the annular groove 43 will allow complete communication between 90 ports 44 and 45, hence completely venting the rear side of the piston 27 to atmosphere.

In the modified form of my controlling valve as shown in Fig. 3, an annular ring 51 is disposed between the end members 29 and 30 of the piston and held therein as by a nut 36 identical to that shown in Fig. 2. Formed in the member 51 is a longitudinally disposed bore 52 within which is disposed a spring pressed valve 53 held therein by a 100 threaded plug 54. In order to allow flow of fluid from the hollow portion of the piston rod 25 through ports 44 and 45, I have provided an annular groove 55 in the periphery of the valve 53, it being noted 105 that in the position of the valve shown in Fig. 3 the right hand shoulder thereof does not quite cover the port 44 so that a slight flow of fluid may be had to the rear side of the piston 27 as was also possible in the 110 preferred form shown in Fig. 2. The spring chamber 52 is vented by means of a passage 56 communicating with the bore of the feed cylinder in advance of the feed piston 27. Upon recoil of the piston 7 the piston 27 115 will be moved rearwardly and due to the inertia of the valve 53, there will be a relative movement between the same and its bore with the result that there will be a greater opening between ports 44 and 45 to 120 allow a greater flow of fluid. The remaining operation of this modified form is generally similar to that of the preferred form.

While I have in this application specifically described two forms which my invention may assume in practice, it will be understood that these forms of the same are shown for purposes of illustration and that the invention may be modified and embodied in 125 various other forms without departing from 130

its spirit or the scope of the appended claims.

What I claim as new and desire to secure by Letters Patent is:

1. A drilling mechanism comprising a drilling motor and fluid operated forward feeding and retracting means therefor including relatively reciprocable cylinder and piston elements, means for controlling the supply of pressure fluid to opposite sides of the feed piston for forward and reverse feeding, and supplemental means for controlling fluid supply for effecting one direction of feeding including a fluid controlling member dependent upon the vibrating action in said mechanism and controlling fluid flow to said feed cylinder to vary the feeding pressure in accordance with the requirements of the work during drilling, while the other direction of movement is independent of said vibratory action.

2. A drilling mechanism comprising a drilling motor and pressure fluid operated forward feeding and retraction means therefor including a feed cylinder having a longitudinally movable piston therein, means for controlling the supply of pressure fluid to opposite sides of the feed piston for forward and reverse feeding, and supplemental means for controlling fluid supply for effecting one movement of said piston including a fluid controlling member dependent upon the vibrating action in said mechanism for controlling fluid flow to said feed cylinder to vary the feeding pressure in accordance with the requirements of the work during drilling, while the other movement is independent of said vibratory action.

3. Drilling mechanism comprising a reciprocable hammer piston, feeding means including a feed cylinder having a fluid actuated piston, and means carried by said latter piston and dependent upon vibrations set up by said hammer piston for controlling fluid flow to said feed cylinder for varying the feeding pressure in accordance with the requirements of the work during drilling.

4. A drilling mechanism comprising a reciprocable hammer piston, pressure fluid operated forward and reverse feeding means therefor including a feed cylinder having a fluid actuated piston, means carried by the latter piston and dependent upon vibrations set up by the hammer piston for controlling fluid flow to the feed cylinder for varying said pressure in accordance with the requirements of the work during drilling, and means whereby upon reverse movement said latter means is inoperative.

5. A drilling mechanism comprising an impact motor, pressure fluid actuated feeding means therefor including relatively reciprocable feeding elements, and valve means continuously open during drilling and variably actuated by the varying recoil of the impact motor when drilling including a member carried by one of said elements, and a cooperating member frictionally engageable with the other element for automatically controlling said feeding means in accordance with the requirements of the work.

In testimony whereof I affix my signature.

CHARLES F. OSGOOD.
